UNITED STATES PATENT OFFICE.

CARL HERING, OF PHILADELPHIA, PENNSYLVANIA.

SECONDARY BATTERY.

SPECIFICATION forming part of Letters Patent No. 429,273, dated June 3, 1890.

Application filed May 24, 1889. Serial No. 311,931. (No model.)

To all whom it may concern:

Be it known that I, CARL HERING, a citizen of the United States, residing at Philadelphia, in the county of Philadelphia, State of Pennsylvania, have invented certain new and useful Improvements in Secondary Batteries, of which the following is a specification.

My invention relates to means of supporting the elements of a secondary battery.

10 The object of my invention is to provide means for supporting the elements in the liquid to enable them to be readily removed, inspected, and renewed without having to unsolder joints, to provide a cheap and simple method for supporting the material of the anodes and cathodes, and to provide replaceable conductors for the same.

Referring to the accompanying drawings, Figure 1 is a vertical cross-section of a cell. 20 Fig. 2 is an elevation of the same with some portion removed. Fig. 3 is a top view of same. Fig. 4 shows two connected conductors for the active material. Fig. 5 shows one block of the active material. Fig. 6 is a vertical cross-section of a cell containing only one pair of blocks.

25 A A are solid blocks of lead peroxide, which may be made by mixing lead oxide with a solution of a salt of lead, pressing the mixture in a mold and drying it and forming it, one side of each being flat and preferably surfaced and the other side being somewhat cylindrical.

B B are blocks of spongy lead.

30 C C are the replaceable conductors, which are made of lead or lead alloy, and which lie against the flat sides of the blocks of active material.

D D are non-conducting straps, preferably 40 perforated, which lie against the rounded sides of the blocks of active material.

E E are rigid plates of non-conducting material.

F F are non-conducting bolts, which pass 45 through the whole set of plates composing a cell and bind them together.

G G are stops of insulated material between the straps D D, by which they are held apart, and the pressure of the bolts is brought to 50 bear upon the blocks A A and B B.

H H are stops of non-conducting material between the straps and at the edges of the

spongy lead blocks B B, relieving them from excessive pressure from the bolts F F. The conductors C C are connected in the ordinary 55 way at their top, forming the terminals of the cell.

I do not bind myself, in the construction and connection of a secondary-battery cell made in the manner described, since, should 60 any other method be hereafter discovered for making porous battery-plates, it is evident that I may use the same without departing from the principles of my invention herein described. It is evident that a 65 cell may contain one pair of blocks, as shown in Fig. 6, or two pairs or four pairs, as shown in Fig. 1, or that its size may be increased in any direction by increasing the number of these sets of blocks vertically or in either direction horizontally, and therewith the capacity. In this way any number of blocks 70 may be combined into one cell. These blocks may be made of one standard size—say of ten ampère hours' capacity—and a cell of any dimensions can thus be built up with them. Small blocks adapted to this purpose are readily molded or pressed, and can therefore be made very cheaply.

The only perishable part—namely, the lead 80 conductors for the peroxide plates—can readily be replaced at small cost, and any defective blocks can readily be renewed, and a block which may break will not necessarily fall out, but will remain in as good working condition 85 as before. The dead-weight is reduced to a minimum. Ample room is given for expansion in all directions, as well as for unequal expansion of the active material and its conductor, and buckling is effectually prevented. 90

I claim as my invention—

1. The combination, in a secondary-battery cell, of two or more blocks of lead peroxide in positions parallel to each other, with removable conducting-plates and two or more 95 blocks of spongy lead in positions parallel to each other, with conducting-plates and removable clamps adapted to hold said blocks severally in contact with their conducting-plates and upon removal to allow said plates and blocks to be removed.

2. The combination, with two lead peroxide blocks, as A, and two spongy lead blocks, as B, having conducting-backings, as C, between

clamps, as E F, having between them straps, as D, with non-conducting stops, as G, between them, of blocks, as H, adapted to receive the pressure of the clamps and relieve the blocks B therefrom.

3. The combination of a peroxide block, as A, and a spongy lead block, as B, having conducting backings, as C, between clamps, as E F, having between them straps, as D, with stops, as G, between them, and blocks, as H, adapted to receive the pressure of the clamps and relieve the blocks B therefrom.

4. The combination, with a peroxide block, as A, and a spongy lead block, as B, conductors, as C, clamps, as E F, and stops, as G and H, of perforated flexible non-conducting straps, as D, adapted to receive the pressure of the clamp, to hold the blocks in contact with their conductors, and to admit the passage of the current through the perforations. 15 20

CARL HERING.
